Des. 228,998

Patented Nov. 6, 1973

228,998

COOKBOOK RACK

Barry M. Rozman, Jamaica, N.Y.
(130 E. 18th St., New York, N.Y. 10003)

Filed Aug. 11, 1971, Ser. No. 171,029

Term of patent 3½ years

Int. Cl. D6—99

U.S. Cl. D6—184

FIG. 1.

FIG. 2.

FIG. 1 is a front and end perspective view of the cookbook rack, embodying the features of my new design; and FIG. 2 is an opposite end elevational view.

I claim:

The ornamental design for a cookbook rack, substantially as shown.
